[57] ABSTRACT

An improvement is provided in the regeneration system of aqueous regenerative processes for the removal of SO₂ from SO₂-containing gas streams which have a

scrubbing system containing (1) a scrubbing zone through which a recirculating stream of sodium, potassium or ammonium thiosulfate solution continuously passes as a vehicle for the SO₂ absorbent—sodium, potassium, or ammonium carbonate—under conditions favorable to the formation of sulfite by the reaction of carbonate and SO₂ and (2) a thiosulfate generation zone in which the sulfite is converted by sulfide to thiosulfate. The improvement comprises converting in a regenerating system, the net make of thiosulfate to sulfide and carbonate by converting one portion of the thiosulfate to formate and the reacting the other portion with said formate.
